Primary Examiner — Barbara Fox*Assistant Examiner* — Mehri F Bajoul*(74) Attorney, Agent, or Firm* — Brinks Gilson & Lione; John C. Freeman(57) **CLAIM**

The ornamental design for a blender, as shown and described.

DESCRIPTION

FIG. 1 is a front perspective view of a blender according to the present invention;

FIG. 2 is a front view thereof;

FIG. 3 is a rear view thereof;

FIG. 4 is a right side view thereof;

FIG. 5 is a left side view thereof;

FIG. 6 is top view thereof; and,

FIG. 7 is a bottom view thereof.

The broken lines shown in the drawings depict portions of the blender that form no part of the claimed design.

1 Claim, 7 Drawing Sheets(56)
